SCREW-FEED GAUGING AND SORTING MACHINE

Samuel I. Snook, Mason, Louis Naveken, Cincinnati, and Charles G. Kehoe, Foster, Ohio, assignors to Remington Arms Company, Inc., Bridgeport, Conn., a corporation of Delaware

Application December 10, 1943, Serial No. 513,660

3 Claims. (Cl. 209—101)

1

The present invention relates to a gauging and sorting machine, particularly adapted for the height gauging and sorting of articles for the purpose of separating them into three groups, one of articles under the minimum gauge, another of articles within the gauge limit, and another of articles over the maximum gauge.

While the invention may be employed for the gauging and sorting of various types of articles, it is especially adapted for the gauging and sorting of primer cups for cartridge cases, and which require that the height be gauged with extreme accuracy so that the primer cup will fit accurately within the pocket in the head of the cartridge case, to the end that it will neither be so high as to interfere with the feeding of the cartridge in the gun, or so low as to prevent the proper engagement of the firing pin therewith.

It is an object of the invention to provide a gauging and sorting machine into which primer cups or other suitable articles may be fed promiscuously in large quantities and will thereupon be guided by gravity into relation with a rotating gauge and feed screw element arranged to move the articles in relation to a series of height gauge elements, the latter being arranged to provide a series of gaps of increasing size through which the respective groups of primer cups pass by gravity.

Another object is to provide a gauging and sorting machine having only a single moving part, namely, the rotating screw element, to the end that the machine will be of relatively simple construction and may be operated continuously for long periods without requiring attention.

A further object is to provide a gauging and sorting machine which may be operated at relatively great speed so that large quantities of the primer cups may be gauged over a relatively short period.

Another object is to provide a gauging and sorting machine which lends itself to multiple unit arrangement with the use of a single power source and moving part, namely, the gauge and feed screw element, it being proposed to provide either one or a series of units along a single screw having feeding thread portions arranged respectively in relation to each unit.

With the above and other objects in view, an embodiment of the invention is shown in the accompanying drawing, and this embodiment will be hereinafter more fully described with reference thereto, and the invention will be finally pointed out in the claims.

2

In the drawing—

Fig. 1 is a front elevation of a gauging and sorting machine, according to the illustrated exemplary embodiment of the invention.

Fig. 2 is a side elevation.

Fig. 3 is a longitudinal sectional view, on an enlarged scale, taken along the line 3—3 of Fig. 2.

Fig. 4 is a transverse vertical sectional view, also on an enlarged scale, taken along the line 4—4 of Fig. 3.

Fig. 5 is a perspective view, partially broken away and partially in section, showing the operative passage of primer cups through the machine.

Similar reference characters indicate corresponding parts throughout the several figures of the drawing.

Referring to the drawing the gauging and sorting machine, according to the exemplary embodiment of the invention illustrated therein, comprises a supporting table 10 upon which there is secured a raised platform 11 to which is attached the horizontal base plate 12 of rectangular form. Vertical side plates 13—13 are secured to the plate 12 adjacent its side edges by means of angle iron strips 14 welded or otherwise suitably secured to the side plate and attached to the base plate by bolts 15. The upper edges of the side plates 13—13 are inclined downwardly and forwardly at an angle calculated as providing the desired gravity feed of the articles to be gauged and sorted, this angle being for instance of the order of 35°. Rectangular recess portions 16—16 are provided at the forward lower ends of the side plates in parallel relation to their inclined upper edges, and have seated therein the ends of a transversely disposed channel member 17 provided at the lower end of an inclined feed plate 18 supported upon the upper inclined edges of the side plates and secured thereto by means of angle iron bars 19—19, welded or otherwise suitably secured to the side plates and secured to the inclined feed plate by means of bolts 20.

At the upper end of the inclined feed plate there is provided an article receiving tray 21, preferably disposed at a slightly inclined downward angle toward the feed plate, and mounted upon a bracket arm 22 secured to the underside of the feed plate by bolts 23 and to the tray 21 by bolts 24, its outer end being supported by a bracket arm 25 secured at its lower end to the base plate 12 by means of bolts 26 and at its upper end to the tray by means of bolts 27. The forward edge of the tray abuts the upper edge of the inclined feed plate 18 in flush relation, so that the articles will slide freely from the tray to the

plate, the upper surface of the plate adjacent the tray being curved, as at 28, upon a relatively large radius, so that the articles will flow freely over this curved surface onto the inclined surface of the feed plate. The rearward edge and the side edges of the tray are provided with upstanding rim portions 29 to retain the articles thereon, it being pointed out that the articles are promiscuously poured or transferred from a shaker plate, hopper or other source to the tray and are then hand fed or forced by accumulation to the inclined feed plate.

Upon the upper surface of the inclined feed plate 18 there are secured adjacent the side edges spacer bars 30—30, curved at their upper end portions to conform to the curved upper end of the feed plate, and between these bars there are provided guide bars 31 and 32, divergent at their upper ends to provide an entrance extending the full length of the tray, and convergent at their lower ends so that the articles are guided by gravity into a relatively narrow exit passage disposed in proximity to one side edge of the plate 18, for a purpose presently to be more fully pointed out. A short curved spacer bar 33 is preferably provided centrally of the entrance passage in parallel relation between the curved upper ends of the bars 30—30. A cover plate 34 preferably formed of transparent material is engaged over the inclined feed plate 18 in parallel spaced relation, being secured upon the upper surfaces of the bars 30, 31, 32 and 33, and being retained at its upper end portion by means of spaced parallel transverse bars 35 and 36, secured to the spacer bars 30 and 33, the bar 35 being arranged along the upper edge of the cover plate, while the bar 36 is arranged slightly below the curved upper end portion. The cover extends for the full length of the guideway between the bars 31 and 32, so that the articles moving from the tray onto the inclined feed plate are positioned and retained with either their upper or their lower ends resting upon the plate, an upset article being prevented from reaching the feed plate by the fact that the diameter of the article is greater than the height of the cover above the plate. The articles A illustrated are primer cups of cylindrical form closed at one end, and of a diameter greater than their height.

The channel member 17 may be integrally formed with the inclined feed plate 18, or it may be separately formed and welded or otherwise suitably secured thereto, the upper inclined feed surface extending in a continuous plane to the channel 37 of the channel member. Within this channel there are secured by bolts 38 a series of gauge blocks, the first gauge block 39 being disposed at the lower exit end of the guideway between the bars 31 and 32, the second gauge block 40 being disposed to the right of the block 39 and having its upper surface in a plane slightly below the plane of the upper surface of the block 39, and the third gauge block 41 being disposed to the right of the gauge block 40 and having its upper surface in a plane slightly below the plane of the upper surface of the block 40. This third gauge block 41 is provided at its right hand end with a recessed portion 42, which constitutes in effect a fourth gauge block having its upper surface in a plane below the plane of the upper surface of the third gauge block 42.

Disposed above the gauge blocks with its axis parallel to their upper surfaces there is provided a gauge and feed screw bar 43 journaled at its left hand end in a bearing block 44 secured in a re-

cessed end portion 45 of the channel member 17 by means of screws 46, and journaled at its right hand end in a bearing block 47 secured in a recessed end portion 48 of the channel member by means of screws 49. At its left hand end the bar projects and is provided with a hand knob 50, while at its right hand end it is connected by a flexible coupling unit 51 to a short shaft 52 journaled in a bearing block 53 provided upon an extension shelf portion 54 at the right hand end of the channel member. Upon the projecting end of this short shaft there is secured a pulley 55 driven from a motor 56 by a drive belt 57.

The screw bar 43 is provided with a spiral thread 58 extending the length of the bar between the bearing blocks 44 and 47. Along the length of the first gauge block 39 at the convergent exit end of the guide passage of the inclined feed plate 18 the pitch of the thread 58 is relatively small, and calculated as providing a space between each successive thread sufficient to comfortably receive one primer cup, while the pitch of the thread extending over the other gauge blocks is relatively larger so that as the articles are fed transversely away from the exit passage they are more widely spaced from each other and are moved at relatively greater speed.

The lower ends of the guide bar 31 and the cover plate 34 extend into close proximity to the screw while the lower end of the guide bar 32 is spaced upwardly from the screw to receive the end of an adjustable guide plate 59 disposed beneath the lower end of the cover plate and extending to the bearing block 47 in parallel relation to the axis of the screw, being adjustably secured by screws 60 engaged through slots 61 in the plate. This plate forms an upper transverse abutment guide for the primer cups as they are fed over the gauge blocks by the screw.

A shield plate 62, preferably formed of transparent material, is provided across the cover plate 34 at a right angle thereto, being retained upon the upper ends of the bearing blocks 45 and 47 by means of angle brackets 63—63, this shield serving to prevent any of the articles which may be inadvertently forced from the tray onto the upper surface of the cover plate from reaching the feed screw, it being pointed out that in the event that an article of less than standard height be permitted to reach the feed screw over the upper surface of the cover plate it may move into engagement with the feed screw adjacent the gauge blocks 41 or 42, and be allowed to flow into the receptacles for receiving standard height or greater than standard height articles. The shield positively prevents this contingency.

The height of the first gauge block 39 is such that the gap between its surface and the feed screw is insufficient to allow any of the articles to pass through the gap, so that all of the articles are fed transversely into relation with the second gauge block 40. The height of the second gauge block is calculated, so that the gap between its surface and the screw is sufficient to allow passage through the gap of those articles of less than standard height, so that these will move by gravity through this gap where they drop over the lower inclined surface of the channel member 17 into a vertically disposed chute 64 through which they fall to an inclined guide chute 65 which directs them into a receptacle 66. The articles of standard height and of greater than standard height are carried from the second gauge block 40 to the third gauge block 41, the height of which is calculated so that standard height articles within

the gauge limits will pass through the gap between its surface and the screw, these articles flowing by gravity to an inclined chute 61 which directs them to a receptacle 68 mounted upon the upper side of the table 10. Articles of greater than standard height will be carried beyond the gauge block 41 to the gauge block portion 42, which is of sufficient depth so that all the articles which are carried beyond the gauge block 41 will pass beneath the screw where they drop through a vertical chute 69 to an inclined guide chute 70 which directs them into a receptacle 71.

While the machine illustrated is a single unit type, that is, a single feed plate provided in relation to the screw, it is pointed out that the arrangement adapts itself to the provision of two or more units arranged side by side and cooperating with a common screw member, which in the case of a multiple unit machine extends along the several units and is provided in relation to each unit with a threaded portion similar to that of the single unit.

The form of the invention illustrated in the drawing and described herein is typical and illustrative only, and it is evident that the invention is capable of embodiments in other forms, all falling within the scope of the appended claims, which are to be broadly construed.

What is claimed is:

1. In a gauging and sorting machine, a feed plate having an exit passage for articles, a series of gauge elements of successively decreasing height extending transversely away from said exit passage in one direction, one of said gauge elements being in direct line with said exit passage, a transversely disposed gauge and feed screw element disposed in spaced opposed relation to said gauge elements adapted to feed articles parallel to its axis along said gauge elements, and providing a series of successively increasing gaps between said screw element and said gauge elements through which said articles are adapted to selectively pass according to their height measurement, and an abutment element extending along said gauge elements in spaced parallel relation to said screw element and adjustably mounted for adjustment toward and away from said screw element.

2. In a gauging and sorting machine, an inclined gravity feed plate having an exit passage for articles at its lower end, a series of gauge elements of successively decreasing height extending transversely away from said exit passage in one direction, one of said gauge elements being in direct line below said exit passage, a transversely disposed gauge and feed screw element disposed in spaced opposed relation to said gauge ele-

ments and having a plurality of threads exposed at said exit passage adapted to feed articles parallel to its axis along said gauge elements, and providing a series of successively increasing gaps between said screw element and said gauge elements through which said articles are adapted to selectively pass according to their height measurement, and an abutment element extending along said gauge elements in spaced parallel relation to said screw element and adjustably mounted for adjustment toward and away from said screw element.

3. In a gauging and sorting machine, an inclined gravity feed plate having an exit passage for articles at its lower end, a series of gauge elements of successively decreasing height extending transversely away from said exit passage in one direction, one of said gauge elements being in direct line below said exit passage, the upper surfaces of said gauge elements being in inclined planes parallel to the plane of said inclined gravity feed plate, a transversely disposed gauge and feed screw element disposed in spaced opposed relation to said gauge elements adapted to feed articles parallel to its axis along said gauge elements, and providing a series of successively increasing gaps between said screw element and said gauge elements through which said articles are adapted to selectively pass downwardly by gravity according to their height measurement, said screw presenting a plurality of threads to said exit passage, and a plurality of chute means arranged to respectively receive articles passing through the respective gaps of said gauge elements.
